[57] CLAIM

The ornamental design for a water jet teeth cleaner, as shown and described.

DESCRIPTION

FIG. 1 is a right side elevational view of a water jet teeth cleaner showing my new design, the left side being a mirror image of that shown;

FIG. 2 is a top plan view thereof;

FIG. 3 is a bottom plan view thereof;

FIG. 4 is a front end elevational view thereof; and

FIG. 5 is a rear end elevational view thereof.
